Specification of Letters Patent.

Patented Nov. 4, 1913.

Application filed June 25, 1912. Serial No. 705,838.

To all whom it may concern:

Be it known that we, HORACE B. GREGORY and IRENE F. GREGORY, citizens of the United States, residing at Brooklyn, in the county 5 of Kings and State of New York, have invented new and useful Improvements in Textile-Fiber Netting, of which the following is a specification.

This invention relates to textile fabric 10 nettings.

The object of the invention is to provide a netting which may be manufactured from knit strands, such as soft finished tape, whereby a net which is light, strong, durable, 15 adapted to preserve its shape, and which possesses other desirable characteristics may be produced.

In the accompanying drawing illustrating the invention,—Figure 1 is a side view 20 of a laundry bag constructed in accordance with the invention. Fig. 2 is a longitudinal section through the bag. Fig. 3 is a plan view showing the body of the netting as it appears prior to being doubled into bag 25 form. Fig. 4 is a view illustrating the manner of uniting the longitudinal edges of the bag body by the lacing strands.

In carrying our invention into practice, we first take a strip of tape 1 and extend the 30 same back and forth in a zigzag manner so as to produce a series of parallel body strands 2, which are connected by marginal loops 3. We then extend at regular intervals and in parallel relation across the 35 strands 2 a series of superposed pairs of connecting strands 4, the strands of each pair being brought to lie against opposite sides of the strands 2 and secured to each other and to said strands 2 by longitudinal 40 rows of stitching 5. By this method of arranging and connecting the strands a net fabric of the desired mesh is produced which may be readily, conveniently and inexpensively made from soft finished knit 45 tape. The ends of the strands are secured to the body of the material or to suitable binders, according to the form in which the net is to be made and use to which it is to be put.

50 In the present instance, we have shown the mode of employing the netting in the manufacture of a laundry bag 6. In the production of such an article from a netting manufactured as described, the body of the

netting, which is of suitable length and 55 width, is folded or doubled upon itself, as illustrated in Fig. 3. The looped ends 3 of the strands 2 at the opposite margins of the folded portions of the netting are thus brought into juxtaposition, and for the purpose of uniting these looped ends to complete the production of the bag, lacing strands 7 are employed. Each of these strands is secured at one end, by sewing or otherwise, to the doubled portion of the netting and is then threaded through the loops 60 3 to form bights 8, through which the lacing strand is threaded to tie the marginal edges of the netting body together, thus forming the bag or similar receptacle. The 65 free marginal edges of the strands 4, the uppermost strand 2 and the free upper extremities of the lacing strand 7 are united by a binder strip 9, preferably composed of ordinary wicking, and which thus constitutes the reinforcing mouth of the bag. For the purpose of closing the mouth of the bag 70 to retain the clothes therein, a fastening strap 11, also preferably of wicking, may be employed. This strap is sewed adjacent 75 one end to the bag and provided at such end with a buckle 12, and the opposite or free end 13 of the strap is provided with eyelets 14 for adjustable engagement with the tongue of the buckle, the eyelets reinforcing the strap so as to prevent the same 80 from being torn or raveled.

By the method of construction described, braid or tape of the character disclosed may be used with advantage in the production 90 of mesh fabrics or nettings, as such fabrics or nettings will be strong, durable and highly flexible, and yet may be washed or subjected to the action of water without shrinking or losing their shape. The construction described obviates the necessity 95 of employing hard finished threads, cords or twines necessarily composed of twisted fibers, in the weaving of which such threads, cords or twines must be twisted about each 100 other. Strands so connected become loose and are weakened or injured under strain, and where the strands are knotted together further weaknesses occur.

Our construction of netting permits of the 105 manufacture of bags and the like, the bodies of which may be made of a single piece of material folded as described.

The invention will be found of great value in the production of bags for holding laundry or clothes to be washed, in that the porous nature of the fabric permits the washing solution to thoroughly permeate the clothes, while also enabling the bleaching and acids used in the process of washing to be much more thoroughly and readily rinsed therefrom than from any other type of woven material, so that the net will retain its pliability and durability. It will, of course, be understood that the netting may be employed in the manufacture of various articles, such as shopping bags, hammocks, seines, tennis nets, etc., and hence we do not limit its mode of use.

We claim:

As a new and improved article of manu-

facture, a network fabric consisting of a single continuous pliable, soft-finished knitted braid extended back and forth in zigzag arrangement to produce parallel strands and interconnecting looped ends all lying in a common plane, rows of similar parallel braids arranged crosswise of said strands and in registering relation upon opposite sides of the same in pairs, and lines of stitching connecting the braids of each pair with each other and with said parallel strands. 20 25

In testimony whereof we affix our signatures in presence of two witnesses. 30
